TOY ROCKET

George T. Boswell, 6710 Kenmont Place, Springfield, Va.

Filed Jan. 14, 1964, Ser. No. 78,187

Term of patent 7 years

(Cl. D34—15)

FIGURE 1 is a perspective view of a toy rocket in an extended operative configuration, showing my new design.

FIGURE 2 is an enlarged perspective of the rocket of FIGURE 1 in a retracted operative configuration.

FIGURE 3 is an enlarged detail view, partly broken away, of the rocket of FIGURE 1.

FIGURE 4 is an enlarged detail view, partly broken away, of the rocket of FIGURE 1, with the perspective taken from slightly below and showing the pedestal portion in a closed position for convenience of storage.

I claim:

The ornamental design for a toy rocket, substantially as shown and described.
